UNITED STATES PATENT OFFICE.

JOHN MILLER, JR., OF BELOIT, WISCONSIN, ASSIGNOR TO CHARLES H. BESLY AND COMPANY, OF CHICAGO, ILLINOIS, A CORPORATION OF ILLINOIS.

GRINDING MACHINE.

Application filed November 24, 1924. Serial No. 751,744.

This invention relates to improvements in grinding machines and more particularly to disc grinding machines used for the finishing of castings and work of like character.

5 The object of the present invention is to provide a construction of a grinding machine having the foregoing characteristics and embodying a new and improved drive whereby a combined oscillatory and rotative movement is imparted to the grinding disc, with the attendant advantages hereinafter more fully set forth.

10 The preferred embodiment of the invention is disclosed in the accompanying drawings in which—

Figure 1 is a view in elevation of the front or grinding end of a disc grinder of the horizontal type;

15 Figure 2 is a view in vertical cross section taken on line 2, 2, of Figure 1;

Figure 3 is an enlarged detail view in vertical section taken on line 3, 3, of Figure 2;

Figure 4 is a similar view taken on line 4, 4, of Figure 2;

20 Figure 5 is an enlarged detail view in horizontal section taken on line 5, 5, of Figure 2 and

25 Figure 6 is a diagrammatic representation showing the typical curves inscribed by the axis of the grinding disc and during several oscillations.

30 As is common in machines of this type, the moving parts are enclosed within a frame or housing, which in this instance is integral with a vertical base or pedestal 1, which rests upon the floor and which supports the frame housing 2 in which the driving mechanism of the grinding disc is enclosed. The housing 2 is generally rounded 35 on its top side and owing to the particular arrangement of the driving mechanism is provided with an additional housing 3 extending above the main housing and offset to the right of its vertical center line.

40 As clearly shown in Figures 2 and 3, the work table 8 comprises a centrally located horizontal platform 8^a, having its surface slotted in the usual manner, so that the various fixtures used for securing the work to 45 the table, may be bolted down. Surrounding the front and side of the central platform 8^a is a trough 8^b, while at the back of this platform is a deeper and wider trough 8^c, extending the full width of the table and

forms the space in which the grinding disk 55 swings.

At the forward end of the machine is located the grinding disc 4, its spindle 5 projecting through the horizontally extending slot 6 in the front wall of the frame housing 2. Integral with the frame housing and projecting forwardly from its front wall is a curved wall 7 extending a short distance beyond the disc and enclosing the top and sides of the space in which the grinding disc 60 swings and rotates. Immediately below the grinding disc is a vertically adjustable work table 8, slidably mounted on vertical guide flanges 9, 9, through the medium of guide ways formed along the side edges of a vertical guide plate 10, integral with the work table 8 and reinforced by two transverse webs 10^a—10^b. The work table is adjusted vertically by a screw shaft 11 journalled at its lower end in a step bearing 12 formed 65 integral with an extension 13 of the base or bed plate of the pedestal 1. Carried at the lower end of the screw shaft 10 is a hand wheel 14 by means of which the work table 70 is elevated or depressed.

75 Located in the upper part of the frame housing 2 and within the portion of the housing extension 3 immediately above the grinding disc 4, is a horizontal shaft 15 extending the full length of the housing and supported at its ends in journal bearings 16, 16, at the forward and rear ends of the frame housing 2 by means of stub shafts 15^a, 15^b. As clearly shown in Figure 2, the portion of the shaft 15 intermediate its stub 80 shafts 15^a, 15^b is of greater diameter and its axis is offset from the axis of the journal bearings or rotation of the shaft, thus forming an eccentric bearing 15^b which rotates 85 with an eccentric motion as the shaft turns 90 on its bearings. Journalled upon and suspended from the eccentric bearing 15^b of the shaft 15 is a swinging motor support 17 consisting of a journal sleeve 17^a extending 95 from the forward bearing 16 to a point short of the rear bearing 16, and integral arms 17^b, 17^c, extending downwardly below the shaft 15 and terminating in a face plate 18 to which is bolted a specially designed 100 motor frame 19 which has a corresponding face plate 19^a. This motor frame 19 supports the driving motor 20, having the usual bearings at each end for the armature shaft

100

105

21 of the motor. The forward end of the armature shaft has direct connection with the spindle 5 of the grinding disc which is likewise journalled in the forward armature bearing which is extended through the slot 6 of the front wall of the housing to the back face of said disc, as clearly shown in Figure 2.

10 Formed integral with the rearmost portion of the motor frame is a vertical shaft bearing 22, in which is journalled a drive shaft 23 in driving connection with the rear end of the armature shaft by a pair of spiral gear wheels 24^a and 24^b keyed to the adjacent ends of the armature shaft and said drive shaft. At the upper end of the drive shaft 23 is a beveled pinion 25, located just below the rear shaft bearing 16 and which meshes with a beveled gear wheel 26 which is keyed to the shaft 15 and at the rear end of the eccentric portion 15^b thereof, between rear shaft bearing 16 and the rear end of the journal sleeve 17^a of the motor support 17.

15 From the foregoing description it will be understood that the motor 20 hangs freely or is suspended from the eccentric portion of the shaft 15 immediately above, as is also the grinding disc 4, in direct driving connection with the motor, and driven thereby 20 at a high rate of speed. Likewise, the motor drives the main eccentric shaft 15 through the drive shaft 23 and intermediate gear wheels, but at a speed considerably less than that of the motor. By reason of the eccentricity of 25 the bearing portion 15^a supporting the motor, the rotation of the shaft imparts a vertical oscillatory or reciprocating motion to the motor and grinding disc corresponding 30 to the amount of eccentricity or throw of the eccentric portion 15^a turning on the journal sleeve of the motor support. Thus, it is seen that from the mechanism already described, two independent movements are imparted to the grinding disc, namely, the rotation of the disc at a high rate of speed 35 about its horizontal axis and an accompanying vertically oscillatory movement at a comparatively slow speed.

40 Another, or third, motion, however, is imparted to the grinding disc by means now to be described:

45 On the rear end stub shaft 15^a of the main shaft 15 is mounted a spur gear 27 enclosed within a gear case 28 exterior to the main frame housing 2. As clearly shown in Figure 5, the gear casing 28 also houses another spur gear 29 which meshes with the spur gear 27. This latter spur gear 29 is keyed 50 to the rear end of a secondary or auxiliary shaft 30, extending the full length of the frame housing 2, parallel with the main shaft 15 but offset laterally therefrom and to the right, as clearly shown in Figure 3. This shaft 30 is journalled at its forward and 55 rear ends in journal bearings 31, 31, integral

with the frame housing, and more specifically at the ends of the housing extension 3.

60 Referring now to Figures 4 and 5, there is keyed to the shaft 30 at a point substantially opposite the rear end of the motor support journal sleeve 17^a, an eccentric assembly consisting of a two part hub member, each part 32, 32, having an integral triangular shaped face plate 32^a extending radially from the hub portions in an upward 65 and downward direction, as is clearly shown in Figure 3. The hubs 32 with their face plates are keyed separately to the shaft with a space between, in which is a circular plate 33, having the form of an eccentric sheave. 70 This eccentric sheave is pivotally connected between the face plates 32^a, 32^a by means of a pin 34 passing through the lower apex of each triangular face plate 32^a and through the sheave at a point offset from its center. 75 The sheave is also connected to the face plates 32^a by means of a bolt 35 which passes through the upward extending portion of each of the face plates and a slot 33^a in the member 33, and described about the fixed 80 pivotal pin 34 as a center, thereby permitting the sheave to be swung about the fixed pivot point to vary its eccentricity with respect to the axis of the shaft 30. Between the slot 33^b in the member 33 and the fixed pivotal 85 pin 34 is a larger slot 33^a likewise subscribed about the fixed center 34 and through which the shaft 30 extends. Manifestly, by virtue of this adjustment, the throw of the eccentric sheave can be varied from concentricity 90 with the shaft 30 to the maximum of eccentricity permitted by the slot and pin adjustment.

95 Mounted on the eccentric sheave 33 is an eccentric strap 36 having an integral arm 100 extending substantially at right angles toward the rearmost depending arm 17^b of the motor support and terminating in a forked end 37. This forked end 37 straddles a lateral projecting boss 38 integral with the 105 motor support below the shaft 15. A journal pin 39 is mounted in this boss, its ends 110 having bearing in the forked ends of the eccentric arm.

115 Having described the auxiliary eccentric shaft drive and its connection with the motor support, the operation of the machine as a whole will now be explained. Bearing in mind the movements imparted to the grinding disc by the motor and by the eccentric motion of the motor support, it will now be seen that a third movement is added by the eccentric on the auxiliary shaft 30, which is driven from the main shaft 15 through the intermeshed spur gears 27 and 29 at the rear of the frame housing. This 120 third motion is a swinging or pendulum movement which carries the motor support, motor and grinding disc back and forth, in an arc of about 60°, or 30° on either side 125 130

of the vertical position of the motor support. Thus, it is seen that the ultimate movement of the grinding disc is a combination of three separate and independent 5 motions, first, the rotation of the disc about its axis; second, a vertical oscillatory movement in the direction of an imaginary line passing through the axis of the spindle and the axis of the main eccentric shaft 15, and 10 thirdly, the pendulum movement imparted from the secondary or auxiliary shaft 30 through the eccentric thereon. Obviously, the motion resulting from the combination of three motions imparted simultaneously is 15 one difficult to describe, but an attempt has been made to illustrate what this motion would be, by the diagrammatic representation of Figure 6, which is intended to indicate the typical path of the center of the 20 disc as it swings back and forth through several strokes or oscillations. From the diagram it will be noted that the motion is quite irregular and without any simple definite sequence or order of convolutions. 25 Moreover, an almost infinite number of motions can be obtained to suit the various kinds of work to be done, first, by changing the spur gears 27 and 28 to secure different gear ratios, since by so doing, the relative 30 speeds of the main and auxiliary eccentric shafts will be changed, thus varying the rate of oscillations to the rate of vertical reciprocations, and hence, producing an entirely 35 different movement. Secondly, by changing the throw of the eccentric on the secondary shaft. This is readily accomplished by loosening the bolt 35 which clamps the eccentric sheave to the face plates 32^b and swinging the eccentric sheave 33 bodily 40 about the fixed pivotal pin 34, thereby increasing or decreasing the eccentricity or throw of the eccentric. Thus, as in Figure 45 3, if the adjustment is such that the maximum throw of the eccentric is obtained by swinging the sheave to the left, the throw can be decreased, even to the extent of bringing the axis of the sheave coincident of the 50 axis of the shaft 30 with the result that an entirely different motion will be produced.

The advantages of the oscillatory movement in the grinding operation are numerous. In the first place, assuming that the work is held stationary and brought in contact with the abrasive surface of the grinding disc, there will be a constantly 55 changing cutting surface presented to the work which gives a much smoother finish and prevents the wear of grooves in the finished surface. In the second place, there 60 is less tendency for the abrasive surface to become clogged with the grindings and gives the surface an opportunity to free itself of the grindings, thus making for speedier grinding action. And finally, the fact that 65 the surface presented to the work is con-

stantly changing, distributes the wear over the entire surface of the disc, thus promoting longer and more uniform wear. Furthermore, the constantly changing surface gives more opportunity for the heat generated in 70 the grinding process to become dissipated, thus preventing the work from becoming overheated with the possibility of warping or distortion of the casting taking place.

I claim as my invention:

1. In a grinding machine, the combination of a rotative shaft having an eccentric bearing portion, a frame suspended from said shaft and journaled on the eccentric bearing portion thereof, a spindle journaled in said frame, a grinding member mounted on said spindle, and means for driving said shaft and spindle at predetermined speeds.

2. In a grinding machine, the combination of a rotative grinding member, a motor in direct driving connection with said grinding member, a support for said motor and grinding member, comprising a shaft having an eccentric bearing portion, a motor support journaled on said eccentric bearing portion and means for driving said shaft.

3. In a grinding machine, the combination of a frame, a horizontal shaft journaled at its ends in said frame and having intermediate eccentric bearing portions, a support frame journaled on the eccentric bearing portion of said shaft and depending therefrom, a spindle journaled in said supporting frame, a motor mounted on said frame and having direct driving connection with said motor and driving mechanism connecting said motor with said shaft.

4. In a grinding machine, the combination of machine frame, a horizontal shaft journaled in said frame, and provided with an eccentric bearing portion, a frame journaled on said bearing portion and depending therefrom, a grinding member journaled at the free end of said frame and a motor in driving connection with said grinding element, and with said shaft.

5. In a grinding machine, the combination of a machine frame, a shaft journaled in said machine frame and having an eccentric bearing portion, a support journaled on said bearing portion, a motor mounted in said support, a grinding disk mounted on the armature shaft of said motor and means for driving said shaft comprising gearing interposed between said shaft and the shaft of the motor.

6. In a grinding machine, the combination of a shaft journaled in the machine frame, and having an eccentric journaled bearing portion, a support journaled on said eccentric bearing portion, a spindle journaled in said support, a motor in driving connection with said spindle, an auxiliary shaft in driven connection with said first mentioned shaft, a connecting rod connecting said aux-

iliary shaft with said support, and driving mechanism operatively connecting said motor with said first mentioned shaft.

7. In a grinding machine, the combination of a machine frame, a shaft journalled at its ends in the machine frame, and having an intermediate eccentric bearing portion, a motor support journalled on said bearing portion, a motor mounted at the lower end of said support, a grinding disc mounted at one end of the motor armature shaft, a drive shaft journalled in said motor support and driven from the other end of said armature shaft, and a gear wheel keyed to the eccentric bearing of said first mentioned shaft, and in driving connection with said drive shaft.

8. In a grinding machine, the combination of a shaft journalled in the machine frame, and having an eccentric bearing portion, a motor support journalled on said bearing and depending therefrom, a motor mounted on said support, a grinding disc mounted at one end of the motor armature shaft, a secondary shaft journalled in said frame and in driven connection with said first mentioned shaft, driving mechanism between said motor and said first mentioned shaft and means carried by said secondary shaft and operatively connected with said motor support for imparting a predetermined movement thereto.

9. In a grinding machine, the combination of a frame, a pair of parallel horizontal shafts journalled in said frame, means for driving said shaft, one of said shafts having an eccentric bearing portion, a support journalled on said eccentric bearing portion, a motor driven spindle journalled in said support and means connecting said support and the other of said shafts for imparting a pendulum motion to said support.

10. In a grinding machine, the combination of a frame, a pair of operatively connected parallel shafts journalled in said frame and provided with eccentric bearing portions, a motor support journalled on the eccentric bearing portion of one of said shafts, a motor and a grinding disk carried by said motor support, an eccentric strap journalled on the bearing portion on the other shaft and operatively connected with said motor support, and speed reducing gearing interposed with said motor and one of said shafts.

11. In a grinding machine, the combination of a frame, a horizontal shaft journalled at its ends in said frame, and provided with an intermediate eccentric bearing portion, a motor suspended from said shaft through the medium of a journal sleeve on said eccentric

bearing portion, a grinding disc directly connected with said motor, a secondary shaft driven from said first mentioned shaft, an eccentric on said secondary shaft and operatively connected with said motor support and means for rotating said first mentioned shaft.

12. In a grinding machine, the combination of a frame, a shaft journalled in said frame and having an eccentric bearing portion, a support journalled on said eccentric bearing and adapted to swing about a horizontal axis, a motor driven spindle mounted on said support, a grinding disk mounted on said spindle, a secondary shaft offset from said first mentioned shaft and having driving connection therewith, means operated by said secondary shaft and connected with said support for imparting an oscillatory movement thereto, and means for imparting a relatively reduced and substantially uniform speed of rotation to said shaft.

13. In a grinding machine, the combination of a shaft having an eccentric bearing portion, a frame depending from said shaft and journalled on said eccentric bearing portion, a spindle journalled in said supporting frame, a motor mounted on said supporting frame and having driving connection with said spindle and said shaft, and means driven by said shaft for imparting oscillatory motion to said supporting frame.

14. In a grinding machine, the combination of a shaft having an eccentric bearing portion, a supporting frame journalled on said eccentric bearing portion, a motor driven spindle mounted on said supporting frame and below said shaft, a shaft rotative about an axis parallel with said first mentioned shaft, means operatively connecting said last mentioned shaft with said support for imparting oscillatory motion thereto, and driving mechanism driven by said motor and operatively connected with said shafts.

15. In a grinding machine, the combination of a shaft having an eccentric bearing portion, a motor support journalled on said bearing portion, a motor mounted on said support below said shaft bearing, a secondary shaft offset from said first mentioned shaft an eccentric sheave and strap mounted on said secondary shaft and connected with said motor support, and means driven by said motor for imparting a relatively slow uniform speed of rotation to said last mentioned shaft to oscillate said motor support.

Signed at Chicago this 20th day of November, 1924.

JOHN MILLER, JR.
